COLLAPSIBLE CRATE

Frank J. Klinka, Milwaukee, Wis.

Application May 10, 1930. Serial No. 451,420

10 Claims. (Cl. 220—6.)

This invention relates to certain new and useful improvements in collapsible crates and refers more particularly to egg crates and has as an object to increase the strength of crates of this character without complicating their structure or adding to their weight.

Heretofore, collapsible egg crates have usually been made of wood and for this reason were very easily and often broken. It is, therefore, another object of this invention to provide a collapsible crate of the character described which is formed entirely of stamped metal.

Another object of this invention is to provide a novel construction for crates of the character described wherein the major elements consist of similar units.

A further object of this invention is to provide the top and bottom members with a plurality of raised ribs which increase the rigidity of the members and cooperate with the cardboard sheets at the bottom and top of the layers of eggs when the crate is filled to produce protecting air spaces or cushions.

And a still further object resides in novel means for readily detachably securing the structure in its position set up for use.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a perspective view of a crate embodying my invention set up for use;

Figure 2 is a detail view of the means for securing the crate in operative position, partly in section and partly in elevation and taken through Figure 1 on the plane of the line 2—2;

Figure 3 is a perspective view of the crate illustrating the manner of collapsing the same; and

Figure 4 is a sectional view taken through Figure 1 on the plane of the line 4—4, and showing the protecting air space at the bottom of the stack of eggs.

Referring now more particularly to the accompanying drawings, in which like numerals designate like parts throughout the several views, the numerals 5 and 6 represent the top and bottom of the crate, respectively, which are each stamped from a sheet of bendable metal and are identical in construction with the exception that the top is provided with a handle 7. Strengthening ribs 8 pressed into the top and the bottom serve to increase the rigidity thereof, and two opposite edges of the top and bottom are curled, as at 9, and 10, respectively.

Rods 11 secured in the curled edges 9 of the top and bottom and having their extended ends received in loops 12 formed on adjacent ends 70 of pins or rods 13 which serve to hingedly connect the four sides 14 of the crate, provide means for hingedly connecting the top and bottom with the sides.

The sides 14 consist of a plurality of slats 14' stamped from bendable metal and provided with longitudinal strengthening ribs 15, and curled ends 15' for the reception of the pins 13. As clearly illustrated, the slats of adjacent sides are staggered with respect to each other so that 80 the curled ends of the slats of two adjacent sides abut and extend throughout the entire height of the pins 13. In this manner the sides are freely hingedly connected to permit their being moved to and from collapsed position and 85 the top and bottom are hingedly connected with the top and bottom edges respectively of opposite sides.

To increase the rigidity of the sides, rods 16 are threaded through aligned apertures 17 90 formed in the slats at a central point by pressing their rib portions slightly outwardly and their side flange portions inwardly. The rods 16 of the sides to which the top and bottom are connected terminate in line with the extreme edges 95 of their outermost slats, but the rods of the other sides are extended, as at 18, beyond the extreme edges of their outermost slats and cooperate with flanges 19 struck inwardly from the top and bottom to further increase the rigidity of the structure when set up for use, the rod ends 18 being looped, as shown, and being received between the flanges 19 when the crate is set up for use.

The inwardly directed flanges 19 do not only strengthen the top and bottom and increase the 105 rigidity of the entire structure, but also partially close the space between the top and bottom and the adjacent slats of the sides at which the flanges are located to preclude the possibility of the crate contents dropping therethrough.

To secure the crate in its set-up position, the curled edges 10 of the top and bottom are provided with latch members 20 which yieldably project their ends beyond the opposite sides of the top and bottom for engagement in loops 21 formed in the ends of the pins 13 opposite the loops 12.

As best shown in Figure 2, the latch members 20 have laterally directed handle portions 22 which project through openings 23 in the curled edges 10 of the top and bottom, and when the latch members are in their fully extended or operative positions, the handle portions 22 are aligned with and received in the hollow of the adjacent strengthening ribs 8. The intermediate portion of the curled edges 10 of the top and bottom, houses an expansive spring 24 which is confined, in a compressed state, between a pair of pins 25 slidably received in the intermediate portion of the curled edges and urged by the spring to about the handle portions 22 of the latch members and normally yieldably urge them to their operative or extended positions.

The outer ends 26 of the openings 23 through which the handle portions of the latch members extend, are cut on an angle so that the action of the spring automatically turns the handle members into parallelism with the top and bottom, as will be readily apparent. Therefore, to retract the latch members 20 to permit their engagement or disengagement from their cooperating loops 21, it is only necessary to turn the handle members to their dotted line positions illustrated in Figure 2, the angular ends 26 of the openings 23 acting as cams to force the latch members inwardly.

The plurality of ribs 8 formed in the top and bottom members besides serving to increase the rigidity of these members, also cooperate with the outermost of transverse cardboard division sheets 27 upon which the layers of eggs 28 rest to provide protecting air spaces or cushions 29, the ribs 8 being assisted by a plurality of inwardly extending tips or projections 30. Breakage of the eggs by sudden jolts and jars during transportation is thus greatly reduced, as the air spaces prevent the eggs coming in contact with the solid surface of the top and bottom members.

In the foregoing description, and the accompanying drawings, the slats 14' forming the sides have been defined and depicted as having medial longitudinal strengthening ribs, but it is understood that the specific cross section of the slats may be varied at will without deviating from the spirit of the invention. However, it is noted that all of the slats 14' are identical in construction, and by forming the top and bottom equally similar in design, the number of operations necessary to produce the individual elements entering into the construction is reduced to a minimum. Crates constructed in accordance with this invention therefore can be produced in large quantities at a relatively low cost.

What I claim as my invention is:

1. A collapsible crate comprising top and bottom members stamped from bendable metal and each having two opposite curled edges, hingedly connecting sides comprising spaced similar slats stamped from bendable metal, means hingedly connecting the slats of adjacent sides, and connecting means carried by the curled edges of the top and bottom adapted for engagement with said means hingedly connecting the sides.

2. A collapsible crate comprising a top, a bottom, and a plurality of sides, each of the sides

being formed of a plurality of spaced slats stamped from bendable metal with longitudinal strengthening ribs and curled ends, the slats of one side being staggered with respect to those of the adjacent side, a hinge member passing through aligned curled ends of the slats of adjacent sides to hingedly connect the same, and a reinforcing member on one of said sides intermediate the ends thereof passing through said strengthening ribs.

3. In a collapsible crate, a metallic top member, a curled edge on said top, a latch member mounted in the curled edge of said top member, means carried by a side of the crate with which the latch member is adapted to engage, means yieldably urging the latch member to operative position, and means for retracting the latch member to permit its engagement and disengagement from its retaining means.

4. A collapsible crate including top and bottom members and sides consisting of similar metal slats, the slats of adjacent sides being hingedly connected in staggered relation whereby certain of the sides have less height than the others, and inwardly directed flanges extended from the marginal edge portions of the top and bottom members adjacent the sides of less height, said inwardly directed flanges increasing the rigidity of the top and bottom members, and cooperating with said sides of less height to form the crate enclosure.

5. In a collapsible crate of the character described, a first side member, a first end member, a first pin pivotally connecting said members, a second side member comprising a plurality of metal strips formed with eyes at the opposite ends thereof, a second pin pivotally connecting said end member to said second side member, a second end member comprising a plurality of metal strips formed with eyes at the opposite ends thereof, a third pin pivotally connecting said second end member to said first side member, a fourth pin pivotally connecting said second end member to said second side member, a bottom supported by said pins, a top pivotally mounted from two of said pins.

6. In a collapsible crate of the character described, a pair of side members and a pair of end members, pins pivotally connecting said side and end members to form a continuous structure, a bottom pivotally connected to two of said pins and retained in place by the other connecting pins a top pivotally connected to two of said pins, and means to detachably connect the top with the other pins so that the pins form a rigid direct connection between the top and bottom of the crate.

7. In a collapsible crate of the character described, a pair of side members and a pair of end members, pins pivotally connecting said side and said end members to form a continuous structure, a bottom member pivotally connected to two of said pins, a top member pivotally connected to two of said pins and means including the remaining connecting pins to secure the top and bottom members in closed position to form a rigid substantially rectangular container with the top and bottom members tied together by the pins.

8. In a collapsible crate of the character described, a plurality of side walls, corner pins pivotally connecting the side walls to form a continuous collapsible structure, loops at the upper and lower ends of the corner pins, a bottom for the crate, projections carried by the bottom and received in two of the lower loops to permanently

- hingedly connect the bottom with said collapsible structure, means carried by the bottom and readily detachably engageable in two other lower loops to hold the side walls in proper position and support the bottom directly from the corner pins, and a top connected with the upper loops of the corner pins, whereby the top and bottom of the crate are directly connected through the corner pins.
- 5 9. In a collapsible crate of the character described, a plurality of side walls, wire corner pins pivotally connecting the side walls to form a continuous collapsible structure, loops formed at the ends of the wire corner pins to hold the pins against displacement from the side walls, a top and a bottom for the crate, and means carried by the top and bottom and permanently engaged in certain of the loops at the opposite ends of the wire corner pins whereby the top and bottom are permanently hingedly connected with the collapsible structure, and means carried by
- 10 the top and bottom and detachably connected with other loops to hold the top and bottom closed with said wire corner pins forming direct connections between the top and bottom.
- 15 10. In a collapsible crate of the character described, four side walls, wire corner pins hingedly connecting the four side walls to form a continuous collapsible structure, loops at the upper and lower ends of the corner pins, a bottom wall, a top wall, projections on said bottom wall engaged in two lower loops to permanently hingedly connect the said bottom wall with the collapsible structure, means carried by said bottom wall and readily detachably engageable in the other two lower loops, projections carried by the top wall and engaged in two upper loops to permanently hingedly connect the top wall with the collapsible structure, and means carried by the top wall and readily detachably engaged in the other two upper loops.
